UNITED STATES PATENT OFFICE

2,643,729

AUDIO PICKUP DEVICE

Charles C. McCracken, Chicago, Ill.

Application April 4, 1951, Serial No. 219,243

1 Claim. (Cl. 181—34)

1

The present invention relates to audio pickup devices finding particular though by no means exclusive utility in connection with hearing aids.

It is a general object of the present invention to provide a novel attachment for a hearing aid which makes the reproduction of sound more pleasant to the user and which increases the effectiveness of the aid in overcoming deficiencies in hearing.

Another object of the invention is to provide an audio pickup device including a microphone element together with physical means operative to limit maximum loudness to the end that reproduction of sharp or sudden noise impulses is minimized.

A further object is to provide an audio pickup device of the above general character in a hearing aid whereby to eliminate painful and disturbing sensations to the user which result from sharp noises such, for example, as those produced by a slamming door, a clanging bell, or the like.

Still another object lies in the provision of means of a simple character which is effective with the aforementioned audio pickup device to minimize the objectionable noises incident to the wearing of a hearing aid known as "clothing scratch."

The objects of the invention thus generally set forth together with other objects and ancillary advantages are attained by the construction and arrangement shown by way of illustration in the accompanying drawing, in which:

Figure 1 is a perspective view of a hearing aid including an audio pickup device embodying the features of the present invention.

Fig. 2 is a fragmentary vertical section taken substantially in the plane of line 2—2 in Fig. 1.

Fig. 3 is a perspective view of a modified form of hearing aid embodying the features of the present invention.

Fig. 4 is a vertical section taken substantially in the plane of line 4—4 in Fig. 3.

Fig. 5 is a fragmentary elevational view of a microphone arrangement intended for use with public address systems and the like and showing in dotted section an audio pickup device embodying the features of the invention.

While illustrative embodiments of the invention have been shown in the drawing and will herein be described in detail, it is to be understood that the intention is not to limit the invention to the specific embodiments shown, but, on the contrary, it is intended to cover all modifications and alternative constructions falling within the spirit and scope of the invention as expressed in the appended claim.

2

Users of hearing aids have been continually plagued by the reproduction by the aids of sharp disturbing noises and scratches. For this reason numerous attempts have been made to overcome or eliminate such objectionable noises which attempts include the provision of acoustical labyrinths, microphone baffles, and various sound absorbing or deadening schemes. To the same end, much effort has been expended in the design of electronic circuits for such devices which serve to limit maximum loudness and to filter out certain frequency ranges. Not only have these attempts not permitted of economical manufacture, but more important, none has proved entirely effectual.

The present invention provides a means of a simple and practical character which has proved effectual to minimize the reproduction of such noises so that when utilized with conventional hearing aid circuits objectionable noises are reduced substantially below the discomfort threshold level.

In accordance with the invention, there is provided in combination with a microphone element a passageway or audio canal to the microphone element for the conduction of an audio wave thereto, and an audio filter shield arranged at the outer end of the passageway, surrounding the same, for receiving and guiding an audio wave impinging thereon into said passageway. The audio filter shield has a flared portion which lies predominantly on one side of the passageway, its surface being interrupted by generally longitudinal ridges and valleys and having a curled peripheral flange, the same being formed in the manner of a human ear.

By way of illustration, an audio pickup device 10 embodying the instant invention is shown applied to a conventional hearing aid which includes a generally rectangular case 12. The case 12 may conveniently be formed of a thermosetting plastic. In the form of the invention illustrated in Figs. 1 and 2, the audio pickup device 10 is formed integral with the hearing aid case 12 and includes a passageway or canal 14 formed by a tubular projection 16 extending inwardly from the front wall of the hearing aid case 12. A microphone element, generally designated 18, is supported adjacent the inner end of the passageway 14 in any suitable manner. Preferably the microphone 18 is enclosed within a resilient covering 20 which serves both to shock-mount the same and to shield it from the reception of audio waves from directions other than by way of the passageway 14.

The outer end of the passageway 14 is outwardly flared and merges smoothly with an audio filter shield 22 which, as above noted, is formed integral with the case 12. The shield 22 is of inverted, generally pear-shaped outline and includes a curled peripheral flange or helix 24 bordering a depressed valley area 26. Adjacent to the valley area is an arcuate, generally longitudinal ridge or antihelix 28 which borders the flared open end or concha of the passageway 14. The shield also includes an arcuate tab-like projection or tragus 29 which partially overlies the outer end of the passageway 14 at one side thereof.

Another form of the invention is shown in Figs. 3 and 4 wherein the audio pickup device 16 is formed separately from the case 12A of the hearing aid in which it is incorporated. Preferably the case 12A is provided with an inwardly extending boss 30 which defines a recess 32 within which the pickup device 16 is partially received. Adjacent the lower right-hand corner of the boss 30 is provided an opening 34 for the reception of the tubular projection 16 of the pickup device which defines the passageway or audio canal 14. The microphone element 18 of the device is, of course, disposed at the inner end of the passageway 14 as previously described.

In this instance the audio filter shield 22 and the tubular projection 16 comprise a one-piece molding of resilient material such, for example, as soft rubber or pliable plastic. As shown, the microphone element 18 is molded within the projection 16 and the latter is provided with an integral rear wall 16a so as to completely enclose the microphone element 18.

Hearing aids are usually supported on an inner garment in a manner such that they are hidden from view by an outer garment. For example, the instrument may be supported in a shirt pocket and concealed by the wearer's coat. This subjects the instrument to highly objectionable noise resulting from the rubbing together of the outer layer of clothing against the inner or underlying layer, or by the rubbing of an outer layer directly against the case of the instrument. The noise produced by this rubbing together of clothing layers produces substantially the same sensation to the wearer of the instrument as that produced in the normal ear by the rubbing together of two pieces of sandpaper. In order to eliminate the production of such noise, or at least to minimize the same, the hearing aid case 12A is provided with a covering or envelope 40 of soft, resilient, porous material such, for example, as sponge rubber. An opening 42 is provided in the covering 40 of the same general shape as that of the recess 32 and the audio pickup device 16 in order not to hinder the operation of the latter and block off the impingement of audio air waves thereon.

It will be observed that the inner surface of the covering 40 lies intimately against the outer surface of the hearing aid casing 12A. Thus there is substantially no relative motion between these two surfaces. If desired, the covering 40 may be fixed to the casing 12A as by cementing. By virtue of the soft resilient character of the covering 40 a layer of clothing bearing thereon

tends to cling to the outer surface of the covering and not slide thereover. It will be apparent, therefore, that since there is substantially no movement between the covering 40 and the case 12A, and little or no movement between the clothing layer and the outer surface of the covering 40, even though the clothing layer might move with respect to the casing 12A, such movement will be accommodated within the resilient covering 40 without the production of any rasping or scratching noise. Should there be movement of the clothing layer with respect to the covering, the character of the covering not only minimizes any noise production but also will absorb it to the end that it is not picked up by the audio device 10.

Turning now to Fig. 5 of the drawing, there is shown an acoustic pickup device incorporated within a microphone structure for a conventional public address system or the like. As shown, the structure includes an audio pickup device 16 like that illustrated in Figs. 3 and 4 housed within a generally ellipsoidal casing 50. The latter includes an imperforate rear shell portion 50a and a foraminated or mesh front portion 50b, and the composite structure is supported on a suitable stand 52. The audio filter shield 22 is disposed substantially in the transverse plane defined by the junction between the two casing sections 50a and 50b, substantially transversely of the casing 50.

It has been observed that the use of an audio pickup device of the character described with conventional amplifying equipment operates to substantially eliminate the production of feedback unless the device is placed directly in front of and in close proximity to the speaker of such equipment.

I claim as my invention:

40 In a hearing aid having a microphone element, the combination of a case for the hearing aid and an audio pickup device, the latter comprising means defining a canal for conducting an audio wave to the microphone element disposed within said case, and an audio filter shield arranged at the outer end of said canal and generally surrounding the same, said filter shield including a flared portion lying predominantly on one side of said canal and including a tab-like projection on the opposite side of said canal partially overlying its outer end, the outer surface of said flared shield portion being interrupted by smoothly merging arcuate ridges and valleys and terminating in a curled peripheral flange, said filter shield being integrally formed with said case and lying generally in a plane parallel and closely adjacent the outer surface of said case.

CHARLES C. McCACKEN.
